CARD INDEX

Herbert Esdaile Short, Wellington, New Zealand,
assignor of one-half to Precision Engineering
Company Limited, Wellington, New Zealand, a
company of New Zealand

Application September 15, 1943, Serial No. 502,400
In New Zealand June 29, 1943

8 Claims. (Cl. 129—16.7)

This invention relates to a card index of the type which comprises a container or drawer and a series of cards arranged therein, each card being provided with projections so arranged and disposed on the lower part of its faces that said projections on each side of the card act as a fulcrum or fulcra which co-act with the fulcrum or fulcra on the card next to the particular face to permit slight pivoting, the arrangement being such that on a card in a limited section being tilted to an appropriate extent by the operator, the lower edge of each card in the limited section is subjected to sufficient pressure from the lower edge of the preceding card to cause pivoting of each card in such section about its appropriate fulcrum or fulcra to provide sufficient room between the upper edge of such cards to enable the operator to identify the particular card required in that section.

Various means have been suggested for giving the aforesaid pivotal effect to card indexes of the type above referred to but have not come into general use, so far as I am aware, owing to the disadvantages attendant upon the practical application of the proposals so far suggested.

By the present invention, however, there has been devised a card index of the type above referred to which is entirely satisfactory for commercial use and has the following advantages:

(a) In the preferred construction, the insert to provide the pivotal effect is removable, so that the cards on removal of said insert, are reduced in bulk to almost their original size for storage purposes.

(b) In the preferred construction, the operator can readily re-insert the inserts if the card should again be required for current purposes.

(c) There is practically no waste of material.

(d) There is complete freedom to type over both of the faces of the card.

(e) In the preferred construction, each card is self-compensating and there is no necessity for the provision of independent compensating cards.

(f) Each card can function in reverse or inverted position.

(g) There is no possibility of a card fouling adjacent cards on re-insertion.

(h) The projections are not so noticeable as to detract substantially from the normal appearance of the card.

The invention consists broadly in a card index of the type described wherein the projections on each card are formed by an insert or inserts located within the thickness of the card to bulge

the faces of each card to form the requisite fulcrum or fulcra.

The invention may further be said to comprise for use in a card index of the type described a card provided with a bulge or bulges on each face formed by an insert or inserts located within the thickness of the card to form the requisite fulcrum or fulcra.

A preferred constructional embodiment of the 10 invention will now however be described with reference to the accompanying drawing in which:

Figure 1 shows an elevation of a card with the inserts applied thereto and showing at one corner a portion of the thickness of the card torn back to show the insert therein,

Figure 2 shows a side elevation of the card,

Figure 3 is a magnified elevation of the inserts,

Figure 4 shows a partial side elevation of a drawer with the cards therein exaggerated in thickness, the side of the drawer being broken away and a finger shown causing pivotal forward movement of the cards,

Figure 5 is a sectional end elevation on the line A—B, Figure 4, and

Figure 6 shows a perspective view of the channel shaped bearer member which rests in the drawer and carries the control plates.

The inserts 3 (see Figure 3) are preferably made of thin Celluloid but may be made of any 30 other approved material such for instance as cardboard. Said inserts 3 are preferably made with a square end 6 and extend to a point 7 at the other end, the edges 8 and 9 extending from the square end 6 to the point 7 being sharpened or tapered. This construction:

(a) Provides a tapering effect in the bulge on the faces of the card which eliminates any tendency to foul other cards on the card being re-inserted into the drawer,

(b) Minimises the possibility of the insert being torn out,

(c) Provides a less obvious projection in the card,

(d) Permits ease in writing over the projection, and at the same time the pointed end 7 enables the inserts 3 to be pressed home into the thickness of the card 1.

Each card is provided with its own compensating insert or inserts whereby the maximum thickness in the upper portion of the card is substantially the same as in the lower portion of the card, inserts 3 preferably made as indicated above being provided to form the thicknesses 2.

To insert said inserts 3 into the thickness of the card, the edge of the card may be penetrated

to the desired distance by a thin knife blade or the like of appropriate size so that on the knife blade being withdrawn, the insert can readily be pushed in and yet be held in place. For general purposes, it is found that the thickness of the insert may approximate the thickness of the card but an increased thickness may be employed so long as the thickness is not so great as to tear the surface of the card on penetration.

It will be understood that where the insert is made of substantially solid material such as Celluloid, the sharpened end of the insert can be driven in through the edge of the card without the necessity of making a slit by the use of a thin knife blade or the like. Again, it will be appreciated that for a permanent insert (that is to say, one which is not readily withdrawable) any convenient and approved quick-setting liquid or semi-liquid such as glue, sealing wax, calcium sulphate or cement, may be injected, the cards being pressed in a mould before the material is set to obtain projections of the desired thickness.

Further, although in the preferred construction there have been shown two inserts in the lower portion with two appropriately placed inserts to provide compensating projects in the upper portion of each card, it will be understood that one centrally disposed insert to provide a pivoting projection could be appropriately provided in the lower portion of the card with a correspondingly disposed insert to provide a compensating projection or bulge in the upper portion of the card, in which case there would obviously be only one pivoting fulcrum on each lower face of each card.

The distance of the upper bulges 2 from the top edge of the card is equal to the distance of the lower bulges 2 from the bottom edge of the card, so that it is immaterial whether any particular card or cards are inserted in the drawer 10 in inverted position.

It is necessary to have a sufficient number of cards in the drawer so that while they are sufficiently adjacent to enable them to pivotally operate on their respective fulcra the cards are not under such compression as to prevent the requisite fanning out at the top.

To assist in regulating the amount the cards can be compressed, and to prevent the tendency of the cards at the front 12 of the drawer 10 to ride up on each other due to forward pressure exerted by the whole weight of the rearward cards when the drawer 10 is moved in and out of the cabinet, control plates or partitions 13 are fitted into the drawer 10 so that same is divided up into the desired number of longitudinal divisions 14 which will each hold the number of cards found most suitable, these control plates supporting the cards at the desired angle.

These control plates 13 are preferably made of rectangular form and are fitted into the drawer 10 by having key form lugs 15, 15a extending from the ends of their bottom edges 16, these lugs 15, 15a being engaged through slotted holes 17 formed in the channel shaped bearers 18 (see Figure 6) so that the tongue portions 19 of the lugs 15, 15a will engage under the upper face 20 of the bearers 18 and permit the control plates 13 to pivot backward and forward to a desired limited extent but prevent said plates 13 from being lifted out of the bearers 18 when same are placed within channels or grooves 21 formed just inward from each side 22 and 22a of the drawer 10 in the bottom 23 thereof.

These bearers 18 are not secured to the drawer 75

10, but merely rest within the channels or grooves 21, and the control plates 13 have to be fitted into the slotted holes 17 of the bearers 18 before the latter are placed into the drawer 10 in that the channels 21 are so spaced apart as to necessitate the tongues 19 being moved to inward positions under the upper faces 20, the key form lugs 15, 15a including their tongues 19 having a slight set in relation to the control plates 13 if so desired to give a slightly greater rearward inclination than forward inclination.

To form the divisions 14 in the drawer 10, there will be a control plate 13a at the front 12 of said drawer which will be inclined towards said front 12, the other control plates 13 all being inclined rearwardly, but as they can pivot as mentioned, on the cards being fanned out from a position at the rear of the drawer, the cards 1 and control plates which are to the front of the opening will be caused to incline forward.

The operation of the invention and the manner in which it is to be performed will be obvious from the preceding description.

I claim:

1. An index card provided in this thickness near one of its horizontal edges with at least one small pocket open at one edge of the card, and an insert in said pocket of a thickness to distend the same so as to form on the opposite faces of said card bulges adapted to cooperate with corresponding bulges on the faces of adjacent cards in a card index and to provide fulcra on which the cards may pivot under pressure.
2. An index card, as claimed in claim 1, in which said bulges occupy corresponding areas on opposite sides of the vertical center line of the card.
3. An index card, as claimed in claim 1, in which said insert consists of a solid piece of material and is withdrawable from said pocket.
4. An index card, as claimed in claim 1, in which said insert consists of a solid piece of material tapering toward its forward end to facilitate insertion into the pocket.
5. An index card, as claimed in claim 1, in which said insert consists of a solid piece of material tapering in thickness toward its forward end.
6. An index card, as claimed in claim 1, in which said insert consists of a solid piece of material tapering in width toward its forward end.
7. An index card provided with two pockets in its thickness near one of its horizontal edges, said pockets being adjacent to and open at the lateral edges of said card, respectively, and inserts in said pockets to distend the same so as to form bulges on the opposite faces and adjacent said horizontal edge of the card.
8. An index card provided near each of its horizontal edges with at least one small pocket open at one edge of the card, and, in each of said pockets, an insert of a thickness to distend the pocket so as to form bulges on the opposite faces of said card, the bulges near either horizontal edge being adapted when the card is used with such edge as its bottom edge to cooperate with corresponding bulges on the faces of adjacent cards in a card index and to provide fulcra on which the cards may pivot under pressure, and the bulges near the other edge of the card compensating for the thickness of the bulges near the bottom edge and permitting use of the card in inverted position.

HERBERT ESDAILE SHORT.
